UNITED STATES PATENT OFFICE.

WILLIAM CAMPBELL, OF NEW YORK, N. Y.

WALL-PAPER.

SPECIFICATION forming part of Letters Patent No. 358,647, dated March 1, 1887.

Application filed November 2, 1886. Serial No. 217,816. (No model.)

To all whom it may concern:

Be it known that I, WILLIAM CAMPBELL, of the city, county, and State of New York, have invented certain new and useful Improvements in Wall-Paper, of which the following is a full, clear, and exact description.

My invention consists of wall-paper ornamented with flock or other pulverized material of different colors, to produce a clouded and variegated appearance.

The invention also consists of the method of applying the pulverized ornamenting material to the surface of the paper, and of the apparatus employed for carrying the process into effect.

Reference is to be had to the accompanying drawings, forming a part of this specification, in which similar letters of reference indicate corresponding parts in all the figures.

Figure 1 illustrates wall-paper ornamented in accordance with my invention. Fig. 2 is a broken side view of the apparatus for coating the paper, and Fig. 3 is a transverse sectional elevation of the same.

A represents an ordinary flocking machine consisting of a suitable casing with an inclined flexible bottom, *a*, and drawing-roller *b*. Along one side of the machine is a shaft, *c*, provided with numerous tappets, *e*, for striking the beaters *d* to cause them to strike the under surface of the bottom *a*. The beaters are pivoted upon the shaft *f*, and are normally held in contact with the bottom *a* by the strong springs *g*, so that when the tappets strike the short ends of the beaters the opposite ends will be lowered against the tension of the springs, which will react when the tappets pass the short ends of the beaters and cause the beaters to strike the under surface of the flexible bottom. Above the flexible bottom *a* of the flocking-machine are held several funnel-shaped receptacles, *h*, in which the pulverized ornamenting material is placed.

The paper to be ornamented is first coated on one surface with size or glue, as illustrated

at *i*, and is then passed along the flexible bottom *a* and attached to the drawing-roller *b*. The ornamenting material is then placed in the receptacles *h*, a different color in each receptacle. The machine is then put in operation, which causes the different colored pulverized material to be beaten up and spread over the paper. At the same time the drawing-roller *b* will be put in motion, which will slowly draw the paper through the machine. The different-colored ornamenting materials will dispose themselves at different parts of the paper, as indicated at *j* and *k*, give distinct solid colors at those parts, and where the different colors meet they will mingle, producing a variegated appearance, as indicated at *l*, thus producing a very handsome and rich ornamented paper.

I am aware that fabrics and also paper have heretofore been ornamented with pulverized dry colors applied during the process of manufacturing, and applied with brushes, as in the patent to William Hedden, No. 249,342, November 8, 1881, and in the patent to W. H. R. Toye, No. 238,991, March 1, 1881, and therefore do not claim, broadly, the ornamentation of paper or other fabric with pulverized dry colors of different colors.

Having thus fully described my invention, I claim as new and desire to secure by Letters Patent—

The method herein described of ornamenting wall-paper with dry pulverized coloring material, which consists in first coating the surface to be ornamented with glue or other adhesive material, and then supplying said surface continuously with dry pulverized coloring material of several colors while the paper is at the same time beaten from the under surface and caused to move or travel continuously, substantially as described.

WILLIAM CAMPBELL.
